2,490,786

CATHODE FOR ELECTRON
DISCHARGE DEVICES

Robert W. Deutsch, Ridgewood, N. J., assignor to
Federal Telephone and Radio Corporation,
New York, N. Y., a corporation of Delaware

Application June 26, 1947, Serial No. 757,136

6 Claims. (Cl. 250—27.5)

1

My invention relates to electron discharge devices and deals particularly with cathode structures for electron discharge devices of the large or power class.

If the cathode electrode of a power tube must dissipate more than a few kilowatts, it is usually fabricated from a number of parallel straight filamentary cathodes disposed cylindrically and coaxial with a cylindrical grid and anode. It is easy to support the filaments at the base end of the tube on short stiff lead-in conductors through the stem, but supports for the outer ends of the filaments are not so simple. The outer ends cannot be braced against the grid or anode partly because of assembly problems in manufacture and partly because there are no commercial insulators available which have satisfactory high-voltage high-frequency characteristics at the operating temperatures.

One of the more common outer-end supports comprises a heavy rod anchored firmly in the stem or base portion of the tube and extending along the center of the cathode to the outer end, each filament wire being attached to the periphery of a transverse metal disc which is centered on the outer end of the support rod. In attempts to prevent bowing and buckling, springs at one end of the cathode assembly have been tried, but degassing and exhausting temperatures usually take the temper out of spring metals, and sticking between parts that are intended to slide cause, rather than prevent, bowing. Unequal expansion and contraction of the filaments further complicate the problem.

One of the objects of my invention, accordingly, is to provide improved cathode assemblies for electron discharge devices.

Another object is to provide a filamentary cathode for power tubes which may be closely held in position and which will not bow or buckle.

The scope of my invention is defined in the appended claims and one embodiment is described in the following specification and shown in the accompanying drawing, in which:

Fig. 1 is a perspective view partly in longitudinal section of my cathode assembly; and

Fig. 2 is a segmental plan view of the outer or depending end of the assembly of Fig. 1.

The particular cathode illustrated comprises a plurality of hair-pin filaments 1, the parallel legs of the filaments being symmetrically spaced about the center-line of the cathode structure. One leg of each filament is solidly attached at its base end, as by eyelet type rivets or bushings 2, to the periphery of a round metal plate 3 and the other

2

leg is similarly attached to a second metal plate 4. The rim of the second plate 4 is serrated as shown to accommodate, without touching, the filament legs secured to the plate 3. The bight 5 of each hairpin comprises a transverse section, with square bends, and with a length corresponding to the desired distance between the legs of the filament. Each plate 3 and 4 solidly supported on lead-in conductors 6 and 7 sealed in a conventional stem or base element. The center support rod 9 is coaxial with the cathode structure and may be fixed at its base end to the tube stem 8 or elsewhere in the tube envelope in any desired manner.

Upon the outer end of the center rod 9 is loosely fitted a bushing 10 of quartz, ceramic or other insulating material, and upon the bushing, in turn, is centered a thin light-weight and flexible metal disc 11. The bushing and disc are loosely secured together as by a retainer cup 12 which also functions as a shield for protection of the bushing from the heat of the filaments. The disc is stamped with a plurality of tongues 13 uniformly spaced along the periphery of the disc, the width of the tongues being slightly less than the length of the hairpin bight and the spacing between tongues being determined by the desired spacing between filaments. Notches 14 are cut in the edge of the disc on either side of the tongue to accurately position and hold the filament. Radial slots 15 are cut in the disc between the tongues. In assembly, the filament bight is simply laid over the tongue in the notches and the tongue is folded over the bight.

The connection between the filament and the disc permits the filament bight to pivot freely under the tongue so that slight flexing of the disc, by elongation or contraction of the filament, can only bear on the filament along a line lengthwise of the filament and will not tend to bow the filament.

If desired, equipotential mid-points of the filament legs may be joined with brace wires for further stiffening as disclosed in the copending application of Andrew Tierney, filed August 3, 1946, Serial No. 688,326, now abandoned, and assigned to the assignee of this application. While freedom of the bushing on the center rod accommodates large changes in the length of the cathode, as when the temperature of the filaments are increased from room to operating temperature, the pivotal connection of each bight and the flexibility of each segment accommodates inequalities in filament expansion.

The cathode of my invention obviates the com-

plications and expense of spring tensioning means, has no sticking metal-to-metal sliding contacts, and will hold the filaments accurately in place without bowing or buckling. Elimination of springs and many of the metal parts heretofore thought necessary not only lightens the structure but simplifies degassing and exhaust.

I claim:

1. A cathode assembly comprising a cylindrical assembly of parallel filamentary cathodes, a support rod coaxial with said assembly, a flexible disc, an insulating bushing freely slideable on said rod, means on said disc loosely supporting said bushing centrally thereof, each filament being fastened at one end of said cathode assembly to a relatively immovable plate and attached at the other end of said cathode assembly to the periphery of said flexible disc to permit unrestrained longitudinal movement of said filaments parallel to said rod.

2. A cathode assembly comprising a cathode filament, said filament being fixed at one end of said cathode assembly, a rod parallel to and spaced from said filament, and a flexible spacer at the other end of said cathode assembly, said spacer having a bushing retainer and an insulated bushing loosely held by said retainer and freely slideable on said rod whereby unrestrained longitudinal expansion and contraction movements of said filament are permitted while transverse displacement thereof is prevented.

3. A cathode structure comprising a support rod, a fixed plate transverse to said rod, a flexible metal disc, an insulating bushing supporting said disc transverse to said rod, said bushing being freely slideable on said rod, a member on said disc loosely retaining said bushing on said disc, a plurality of parallel filamentary cathodes attached at opposite ends of said cathode structure to said plate and said disc, said flexible disc having a radial slot between each pair of filamentary cathodes.

5. A cathode structure comprising a thin metal disc having symmetrically spaced radial slots, a plurality of hairpin shaped filamentary cathodes, the bights of said cathodes being pivotally attached to the periphery of said disc between said slots, and the legs of said cathodes being parallel and extending substantially normal to said disc.

10. 5. The cathode structure defined in claim 4 further comprising integral tongues on the periphery of said disc between said slots, notches in the periphery of the disc on either side of each tongue, each tongue encircling the bight of one filamentary cathode and holding the legs of the cathode in said notches.

15. 6. A cathode structure comprising a plurality of fixedly supported lead-in conductors, close spaced parallel plates transverse to said conductors and electrically connected to different conductors, a fixedly supported center support rod extending centrally through said plates, an insulating bushing freely slideable on said rod near the outer end of the rod, a flexible metal disc centered and loosely retained on said bushing, said disc having symmetrical radial slots, a plurality of hairpin filamentary cathodes, the ends of the 20 legs of each cathode being connected, respectively, to said plates, and the bight of each cathode being connected to the periphery of said disc between said slots.
